UNITED STATES PATENT OFFICE.

CHARLES F. McBEE, OF ATHENS, OHIO, ASSIGNOR TO THE McBEE BINDER CO., A CORPORATION OF OHIO.

ADJUSTABLE EVENER BOARD FOR BINDING MACHINES.

Application filed February 2, 1921. Serial No. 441,803.

The object of my invention is to provide an adjustable means for an evener board for a receptacle to receive and retain material to be perforated which will be simple 5 in construction and efficient in service, and which will be adapted to be applied to any standard perforating, punching or binding machine.

In preparing papers, or the like, for receiving perforations to adapt them for either binding or loose leaf filing, it is often necessary to locate these perforations at different distances from the forward edge surface of the papers so that they will easily fit into 15 the particular binder desired.

My invention consists of the details of construction illustrated in the drawings forming a part of this application, and as described and claimed in the attached specifications, in which—

Fig. 1 shows a sectional view of the base of a binding machine to which my device is attached, said section being taken on the line 1—1 of Fig. 2.

Fig. 2 shows a vertical sectional view taken on the line 2—2 of Fig. 1.

Referring to the accompanying drawings, the reference numeral 10 is used to indicate the base of a binding machine having 30 a forward cross bar 11 and a rear cross bar 12, each of which are provided with orifices to receive for slidable movement, the parallel rods 14 and 15. On the forward ends of the cross bars, immediately forward of the cross bar 11 I have secured an upwardly projecting plate 16 which is designed to be in advance of, and parallel with, the punching or perforating devices of the binding machine (not shown). A

handle bar 17 joins the rear ends of the 40 parallel rods 14 and 15 and is designed for use in sliding the rods to the desired position. Set screws 18 are secured in one of the cross bars so as to contact with their respective rods and to be adapted to hold 45 the rods in any desired position.

The plate 16, in the construction of the binding machine, is designed to be positioned on a line slightly in advance of the perforating apparatus, which obviously is 50 above the base 10. The material to be bound is placed upon the base and moved forward to contact with the plate 16, which thus causes the papers, or the like, to be evened to receive the perforations in the 55 proper places. As it is often desired to have these perforations at varying distances from the edge (for filing in different style loose binders), it is obvious that this purpose may be accomplished by changing the 60 position of my evener plate 16, by moving the rods 14 and 15, as is clearly indicated by the dotted lines in Fig. 1.

Having thus described my invention what I claim and desire to secure by Letters Patent of the United States is:—

An evener device for binding machines comprising a base and cross bars secured therein, a pair of parallel rods slidably secured in said cross bars, an evener plate 70 mounted on said rods, a handle bar secured to, and joining the ends of, said rods for use in positioning the slidable rods, and means to retain the rods in any desired position.

In testimony whereof I have signed the foregoing specification.

CHARLES F. McBEE.
